UNITED STATES PATENT OFFICE.

UTLEY WEDGE, OF ARDMORE, PENNSYLVANIA.

RABBLES AND RABBLE-ARM FOR METALLURGICAL FURNACES.

1,100,461.

Specification of Letters Patent. Patented June 16, 1914.

Application filed December 27, 1912. Serial No. 738,854.

To all whom it may concern:

Be it known that I, UTLEY WEDGE, a citizen of the United States, residing at Ardmore, Pennsylvania, have invented certain 5 Improvements in Rabbles and Rabble-Arms for Metallurgical Furnaces, of which the following is a specification.

My invention relates to that class of metallurgical furnaces which have rabble arms for 10 stirring or feeding the material deposited upon the hearth or hearths of the furnace.

Heretofore different means have been employed for cooling the rabble arms by circulating water or other cooling fluid through 15 passages in the arms, but, so far as I know, no attempts have been made to cool the rabbles themselves, and such cooling of the rabbles therefore constitutes the purpose of my present invention.

20 In the accompanying drawings—Figure 1 is a view, partly in top or plan view and partly in horizontal section, of a rabble arm illustrating one means in accordance with my invention for cooling the rabbles; Fig. 2 is a longitudinal section on the line *a—a*, Fig. 1; Fig. 3 is a view, partly in end elevation and partly in section, on the line *b—b*, Fig. 1; Figs. 4 and 5 are longitudinal vertical sections of the inner portions of rabble 25 arms showing modified means for conveying the cooling fluid to and from the arm; Fig. 6 is a transverse section on the line *c—c*, Fig. 4, and Fig. 7 is a horizontal section of another type of rabble arm embodying my 30 invention.

Referring in the first instance to Figs. 1, 2 and 3 of the drawing, 1 represents a rabble arm which is secured at its inner end to a ring 2 mounted upon any available support, 40 as, for instance, upon the central rotating shaft 3 of a cylindrical furnace of the type which is provided with such shaft. The blades or rabbles 4 are cast or otherwise formed integrally with the rabble arm, from 45 which they depend and upon which they are disposed at an angle to the longitudinal line of the rabble arm, so that, as the latter rotates with the shaft 3, or is otherwise moved over the hearth upon which the material is 50 deposited, such material will be stirred by the rabbles and will be moved over the hearth because of the inclination of the rabbles in respect to their line of travel. On the back of the rabble arm, and also formed 55 integral therewith, are a series of helically

disposed ribs 5 each extending from one end of one rabble to the opposite end of the adjoining rabble, as shown in Fig. 1. Both the rabbles 4 and the ribs 5 are hollow and communicate with each other, so that continuous passage is provided from the rabble at the outer end of the arm to the rabble at the inner end of the same. The rabble arm 1 is also hollow and communicates at its outer end through a passage 6 with one end 60 of the outermost rabble 4, as shown in Fig. 3, the opposite end of said outermost rabble communicating through the first rib 5 with the next adjoining rabble which communicates through the second rib 5 with the third 70 rabble, and so on throughout the series. The hollow rabble arm has, at its inner end, two passages 7 and 8, the passage 7 communicating with the hollow arm and the passage 8 communicating with the innermost rabble 75 4, as shown in Fig. 1. The inner ends of the passages 7 and 8 are closed by a plate 9 secured to the inner end of the rabble arm, as shown in Fig. 2, and this plate carries two pipes 10 and 11, one for supplying cooling 80 fluid to the passage 7 and the other for discharging said fluid from the passage 8 after it has circulated through the rabble arm and rabbles, or the direction of flow may be the reverse of this, if desired. By this means 85 there is a constant circulation of the cooling agent through the rabbles as well as through the rabble arm and the hollow ribs on the back of the same, consequently the rabbles as well as the rabble arm will be cooled and 90 the rapid destruction or impairment of the rabbles by the heat of the furnace will be prevented and the frequent replacement of said rabbles therefore rendered unnecessary.

The cooled rabbles also serve to prevent 95 overheating of the material acted upon, thereby overcoming an objection sometimes encountered in treating material which is unfavorably affected by an excess of heat, and said cooled rabbles may also be used for 100 cooling the material in one or more of the treating chambers of the furnace, after it has been heated in the preceding chambers.

In the constructions shown in Figs. 4 and 5 the passages within the rabbles 4 and ribs 105 5 extend inwardly to the central opening of the rabble arm but the inner ends of these passages, except as hereinafter noted, are closed by a pipe 12, which fills the central opening of the arm. Said pipe 12 should 110

- extend through the arm from the inner end of the same to a point just short of the entrance to the outermost rabble, so as not to close the passages contained in the latter.
- 5 The pipe 10 communicates at the inner end of the arm with the pipe 12 and the pipe 11 communicates with the inner end of a passage 13 formed in the rabble arm at a point above the pipe 12, such passage 13 communicating at its inner end with the innermost rib 5 of the arm, as shown in Fig. 4. The rabble arm shown in Fig. 5 is similar to that shown in Fig. 4 so far as regards the use of the pipe 12 for closing the inner end 10 of the passages in the rabbles 4 and ribs 5 but said pipe 12 stops short of the inner end of the rabble arm, the latter being provided with passages 7^a and 8^a similar to those of the rabble arm shown in Fig. 1, the passage 15 7^a communicating with the pipe 12 and the passages 8^a with the innermost rib 5 of the rabble arm.

In the rabble arms shown in Fig. 7 the back ribs on the arm are dispensed with and 20 the hollow rabbles communicate with one another through chambers or passages formed in the hollow rabble arm itself. In the construction shown in Fig. 7 the hollow rabble arm is provided with a central partition 14 and a series of transverse partitions 15 extending from said central partition to the front or back wall of the arm so as to divide the hollow arm into a series of chambers which I have numbered 16^a, 16^b, 16^c, 25 16^d, etc., the passage 7 of the arm communicating with the chamber 16^a at the inner end of the arm, and the chamber 16^b, at the outer end of the arm, communicating, through a pipe 17, or other available return conduit, 30 with the passage 8 at the inner end of the arm. The chamber 16^a communicates with one end of the innermost rabble 4 whose opposite end communicates with the chamber 16^b, and the latter also communicates 35 with one end of the next outer rabble 4 whose opposite end communicates with the chamber 16^c, the next outer rabble connecting the chambers 16^c and 16^d, the next outer rabble connecting the chambers 16^d and 16^e, 40 and so on to the end of the series, the outermost rabble discharging into the chamber 16^e whence the cooling agent is returned 45 through the conduit 17 to the passage 8.

I claim:

- 50 55 1. The combination of a rabble arm having a series of projecting rabbles thereon, means providing communication from rabble to rabble of the series, and means for supplying water to the rabble at one end of

the series and discharging it from the rabble 60 at the other end of the series.

2. The combination of a hollow rabble arm, a series of connected rabbles projecting therefrom and in communication therewith at one end of the arm, means for discharging water from the rabble at the opposite end of the arm, means for supplying water to said rabble arm at the same end from which the water is discharged from said rabble, whereby said water is first caused to circulate through the arm in one direction and then through the series of rabbles in the opposite direction.

65 70 75 3. A rabble arm having a series of chambered rabbles projecting from the under side of the same and a series of chambered ribs extending from rabble to rabble of the series and crossing over the back of the rabble arm.

4. The combination of the hollow rabble arm, a series of chambered rabbles projecting from the under side of said arm, a series of chambered ribs extending from rabble to rabble of the series and crossing over the back of the arm, a communication between the end rabble of the series and one end of the hollow arm, and means for discharging water from the opposite end rabble at the other end of the arm.

80 85 90 95 5. The combination of a hollow rabble arm, a series of chambered rabbles disposed on the under side of the same, a series of chambered ribs disposed over the back of the arm and serving to connect one end of one rabble to the opposite end of the adjoining rabble throughout the series, means for conveying water from the hollow arm to the rabble at one end of the series, and means for discharging water from the rabble at the other end of the series.

100 105 6. A rabble arm having chambered rabbles, and chambered ribs each connecting an end of one rabble to an end of the adjoining rabble, and means for circulating a cooling fluid through said rabbles and ribs from end to end of the series.

7. A rabble arm having chambered rabbles thereon, and chambered ribs each connecting one end of one rabble to the opposite end of the adjoining rabble, and means for circulating a cooling fluid through said rabbles and ribs.

In testimony whereof, I have signed my name to this specification, in the presence of two subscribing witnesses.

UTLEY WEDGE.
